UNITED STATES PATENT OFFICE.

JAMES OSBORN STEPHENS, OF BIG ISLAND, VIRGINIA, ASSIGNOR OF ONE-THIRD TO JOHN MARVIN STEPHENS AND ONE-THIRD TO HARRY RANDOLPH, BOTH OF MCCOMAS, WEST VIRGINIA.

INTERNAL-COMBUSTION ENGINE.

1,212,581.

Specification of Letters Patent. Patented Jan. 16, 1917.

Application filed January 3, 1916. Serial No. 69,904.

To all whom it may concern:

Be it known that I, JAMES OSBORN STEPHENS, a citizen of the United States, and a resident of Big Island, in the county 5 of Bedford and State of Virginia, have invented certain new and useful Improvements in Internal-Combustion Engines, of which the following is a specification.

My invention relates to improvements in 10 internal combustion engines and more particularly to novel means for conveying the gas to and from the cylinders and it consists in the combinations, constructions and arrangements of parts herein described and 15 claimed.

Another object of my invention consists in the provision of a multiple cylinder V type engine in which is embodied a valve of 20 a design whereby it is adapted to accommodate the functions of the twin cylinders between which it is located.

Another object of the invention consists in the provision of means insuring the seating of the valve to prevent the escape of the 25 gases from the parts.

Other objects and advantages will appear in the following specification, reference being had to the accompanying drawings in which—

30 Figure 1 is a vertical section of an engine embodying the improved features the view being a section taken substantially on line 1—1 on Fig. 4. Fig. 2 is a detail plan view showing the current distributor. Fig. 3 is a 35 cross section on line 3—3 on Fig. 2. Fig. 4 is a cross section on line 4—4 on Fig. 1. Fig. 5 is a detail cross section on line 5—5 on Fig. 1. Fig. 6 is a perspective view of the 40 valve. Fig. 7 is a vertical section of the engine showing a modified form of valve driving gearing.

In the drawings, 1 represents the crank case which is provided with suitable bearings in which the crank shaft 2 is mounted. 45 The crank case 1 is formed in a suitable manner to receive the oppositely disposed cylinders 3 and 4 which are bolted over openings in the case. Pistons 5 and 6 are located in the bores of the cylinders and the 50 pistons are connected with the crank 7 through connecting rods 8 and 9 which serve to turn the shaft 2 as the pistons 5 and 6 are reciprocated.

The cylinders 3 and 4 which are prefer-

ably cast *en bloc* are approximately 120° 55 apart as shown, the cylinder body having a centrally located valve recess 10 which is of an inverted cone-shape. Registering with the valve recess 10 is an annular gas exhaust chamber 11 and an annular gas inlet chamber 12. The exhaust chamber 11 has a flanged outlet 13 at one side (see Fig. 4) to which an exhaust pipe is bolted to convey the burnt gases to a suitable place of discharge. The gas inlet chamber 12 communicates with a carbureter 14 which forms the gaseous mixture which is supplied to the chamber 12 by the suction caused by the pistons 5 and 6 in a manner presently to be explained. The carbureter gas intake is suitably controlled by a valve 14 as is common in devices of this kind.

It should be noted that in practice the engine may be composed of multiple twin cylinders and in the event of such a construction, the exhaust and inlet openings from the respective annular chambers 11 and 12 are connected so that there may be a common outlet and inlet. If the engine consists of a pair of twin cylinders only the 75 exhaust ports 13 are connected to a common union and from thence the gases will be conducted to the atmosphere. Similarly the inlet ports are connected to a common union 80 which is connected to the carbureter located 85 between the pairs of cylinders.

A valve 15 is located in the seat 10 and is provided with a shaft 16 at the top and a square opening 17 at the bottom. After the valve 15 is placed, the seat 10 is covered by a 90 cap plate 18 which has a water passage with which the water jacket of the cylinders and valve seat communicates. One valve 15 is provided for each pair of cylinders as shown in Figs. 1 and 4.

The tops of the cylinders 3 and 4 communicate with the recess 10 by single ports 19 and 20 which serve the combined functions of inlet and exhaust ports. Disposed diagonally through the upper part of the valve body is an exhaust passage 21. The upper end of the passage 21 revolves in the plane of the exhaust chamber 11 while the lower end revolves in the plane of the adjacent ends of the cylinder ports 19 and 20 as 105 shown in Fig. 1.

Arranged in a plane at right angles to that of the passage 21 and disposed diag-

onally within the body of the valve 15 is a gas inlet passage 22. The lower end of the passage 22 revolves in the plane of the gas chamber 12 and like the upper end of the passage 21, is in constant communication with the adjacent chamber. The upper end of the passage 22 revolves in the plane of the adjacent ends of the cylinder ports 19 and 20. The arrangement of the passages 21 and 22 provides intermittent communication of the upper ends of the cylinders 3 and 4 with the exhaust and inlet chambers respectively at the proper times when the cylinders perform the corresponding functions in their cycles of operation.

The valve 15 is turned by a shaft 23 which has a square end that fits into the recess 17 as shown in Fig. 1. A bevel gear 24 is mounted on the lower end of the shaft 23 and meshes with a bevel pinion 25, on the shaft 2 of the engine. The engine being of the 4 cycle type, the gearing is of a ratio of two to one so that the crank shaft makes two revolutions to one of the valve 15. The shaft 23 is supported by a thrust collar 26 which bears against a bearing portion of the cylinder casting as shown, another bearing 27 being shown near the bottom of the shaft.

The valve 15 will ordinarily remain in contact with its seat on account of its inverted cone shape but in order to prevent it from moving upwardly which it might do when the engine is severely jarred, a tension device is provided to hold the valve to its seat. The tension device consists of a spring 28 which is coiled about the shaft 23 and which engages a cupped washer 29 at the top and a pendent boss 30 at the bottom. The washer 29 is held in place by a pin which passes through the shaft above the washer while the boss 30 is pendently supported by arms from the bottom of the valve 15 as shown.

Since the shaft 23 is a fixture so far as its vertical thrust is concerned the tension of the spring 28 will be directed downwardly against the boss 30 and hold the conical valve 15 to its seat and so prevent the leakage of gases between the valve and the seat.

The compressed charges of gas in the cylinders are ignited by a spark from the plugs 31 and 32 which are located in the usual high-tension circuit (not shown). The current is distributed to the low-tension circuit by a current distributor which comprises an arm 33 mounted on the upper end of the valve shaft 16 as shown in Figs. 2 and 3. A contact roller 34 is located at one end of another arm which is in turn pivoted to the end of the arm 33. A spring 35 joined to these two arms holds the roller 34 in contact with the internal face of a ring 36 of insulating material, contacts 37 and 38 being embedded in the ring 36. The roller in contacting one or the other of the points 37 and

38 completes the circuit and causes the compressed gaseous charge in the corresponding engine cylinder to be ignited in the manner described.

Fig. 7 shows the engine substantially as it is in Fig. 1 but with the cylinders and other parts constructed on an improved design. In this view the cylinders are about 65° apart. The piston 5 is shown as just beginning its compressed stroke while the piston 6 is exhausting a previously exploded charge through the passage 21 of the valve 15. The valve 15, in this embodiment, is rotated by the bevel pinion 39 which meshes with a bevel pinion 40 on the lower end of the valve shaft 23. The pinion 39 is mounted on one end of a horizontal drive shaft 41 which is suitably mounted in bearings on the crank case 1. A large gear 42 is located on the other end of the shaft 41 and is driven by an intermeshing pinion 43 which is mounted on the crank shaft 2. The valve is held to its seat by a spring 28 similarly as shown in Fig. 1, the spring serving to take up wear as well as to hold the valve in place. It is also a matter of importance that in the actual manufacture of the device, the cylinders, valve, seat, and gas inlet and exhaust chambers can be cast in one block this being possible by the peculiar arrangement of these different parts.

Having thus described the construction of the engine the operation thereof is as follows: By reference to Fig. 1 it will be seen that the piston 5 of cylinder 3 has nearly completed its exhausting stroke. At this time the passage 21 is in registration with the cylinder port 19 and the burnt charge is being forced into the chamber 11 and from thence to the atmosphere. The piston 6 has compressed a charge of gas which is being ignited since the electrical circuit has been completed by the engagement of the roller 34 with the contact point 37 of the distributor. At this time the port 20 is closed by the wall of the valve 15 and remains closed until the piston completes its outward or working stroke. At the end of this stroke the lower end of the passage 21 will have come into registration with the port 20 and when the piston then returns, the burnt gases ahead of it will be forced into the chamber 11 similarly as explained for the exhausting of the cylinder 3. Again referring to piston 5; when the piston 5 travels its outward or suction stroke after having exhausted the cylinder of the burnt gases, the passage 22 will be in registration with the port 12 and gas will be drawn into the cylinder. From the foregoing it will be seen that the inlet and exhaust passages 21 and 22 come into registration with the cylinder ports 19 and 20 and during each cycle of operation of the respective pistons.

The embodiment of the tension device in

a valve of the shape shown will insure against objectionable leakage of gases around the ports and passages and while I may make numerous modifications in the device I can still retain the simplicity of the structure and remain within the scope of the claims.

I claim:—

1. The combination of an engine body having a cylinder and a conical valve recess adjacent to the cylinder, and a conical valve inclosed within the cylinder, and having a square opening in its lower smaller end, a shaft connected with the valve having a square upper end fitting into the square opening of the valve and having a fixed washer adjacent to the lower end of the valve, a bearing in the cylinder for said shaft preventing its upward movement, a collar rigidly connected to the valve, said collar being spaced from the lower end of the valve and disposed about the said shaft below said washer, and a compression screw located between the collar and the washer 25 to hold the valve properly seated within the valve recess at all times.
2. In an engine, the combination of a cylinder having a port and a conical valve recess at one side communicating with the port, a piston within the cylinder, a power shaft with which the piston is connected, said valve recess having vertically spaced annular chambers, a conical valve seated in the recess and having diagonal passages establishing communication between the said

annular chamber and the cylinder port and located wholly between the ends of the valve, upper and lower shafts projecting vertically and axially from the said valve, ignition means controlled by the upper shaft, and a connection between the lower shaft and the said collar shaft for rotating the said valve.

3. In an engine, the combination of a cylinder having a port and a conical valve recess at one side communicating with the port, a piston within the cylinder, a power shaft with which the piston is connected, said valve recess having vertically spaced annular chambers, a conical valve seated in the recess and having diagonal passages establishing communication between the said annular chamber and the cylinder port and located wholly between the ends of the valve, upper and lower shafts projecting vertically and axially from the said valve, ignition means controlled by the upper shaft, and a connection between the lower shaft and the said collar shaft for rotating the said valve, said lower shaft having a longitudinally adjustable connection with the lower end of the valve, and a spring engaging the valve and engaging a portion of the said lower shaft whereby to adjust the valve relatively to the said shaft and maintain the former properly seated within the valve recess at all times.

JAMES OSBORN STEPHENS.
